21, 1938, Serial No. 220,450

3 Claims. (Cl. 8—155)

This application is a division of our co-pending application Serial No. 39,586, filed September 7, 1935, and issued into Patent No. 2,157,135 on May 9, 1939.

5 The present invention relates to a method of dyeing or otherwise similarly treating packages of textile material. By the term "package" as employed in the following specification and claims is meant any wound mass of textile material 10 whatever its character or form and whether or not supported either from within or without.

By the usual method of dyeing, bleaching, mordanting or otherwise treating packages of textile material in a kier a treating fluid is surged through a plurality of the packages under pressure. Considerable difficulty has been experienced in passing the same volume of fluid through each package and as a result the material in the different packages is not uniformly treated. 15 For example, when the packages of the material are treated with a dye-liquor, and particularly packages of synthetic fibers commonly known as "artificial silk" or "rayon", the several packages do not have a uniform color shade. This difficulty is caused by variations in the density of packages wound on different spindles due to variations in the tension applied to the yarn, the pressure of the thread-guide on the package, and the spacing of the coils during winding. The 20 varying degrees of density of the packages varies their porosity which, in turn, varies the permeability of the packages to the flow of a treating fluid.

When a series of packages of varying permeability are treated in a kier in the manner explained above, a larger proportion of the treating fluid flows through the packages having the greatest permeability and a lesser amount of the fluid passes through the packages having a lesser 25 permeability. As a result the different packages are subjected to the treating fluid in varying degrees. When dyeing the dye-liquor is absorbed in varying quantities in the different packages which gives a variation in the color shades. To 30 avoid such inequalities it has been the practice to test the density of packages by their feel to the hand. Such a method of testing the permeability of packages has been found to be entirely unreliable. For example, it has been found 35 in actual practice that packages which feel too soft take the same color shade as the other packages of a batch when dyed, while packages having the right feel to the hand do not always take the same color shade as the other packages of a batch when dyed. That is to say, the apparent

density of a package as determined by feeling with the hand definitely has been proven not to be a true indication of the permeability of the package.

One object of the present invention is to provide a method of dyeing or otherwise similarly treating textile packages so that all the packages of a batch will be uniformly treated. 5

Another object of the invention is to provide a method for the purpose specified including the 10 preliminary steps of accurately testing the permeability of each individual package and grouping those packages having the same permeability to provide a batch for treatment under the same conditions. 15

Another object of the invention is to test the 20 permeability of individual packages wound on different machines so that the source of improperly wound packages can be quickly detected and the fault corrected.

Still another object of the invention is to provide a testing step for the purpose specified which includes measuring the pressure necessary to force a stream of testing fluid through each package at a constant rate. 25

Further objects of the invention are set forth in the following specification which describes the method and a preferred form of apparatus for practicing the testing step, by way of example, as illustrated by the accompanying drawings. 30 In the drawings:

Fig. 1 is a perspective view of a testing apparatus showing a package mounted thereon prior to a testing operation; and

Fig. 2 is a longitudinal, sectional view of the 35 apparatus illustrated in Fig. 1 showing the relationship of the elements while a testing operation is being performed.

The packages to be treated by the present method are preferably wound on hollow porous 40 cores which may be either rigid or compressible, but the invention in its broadest aspect includes the testing of packages in any form such as cops, cones, cheeses, cakes, jack-spoils, beams, and the like. In accordance with the present invention the individual packages are first tested to determine their relative permeability. Air is usually used as the testing medium because of the ease and convenience with which it may be supplied and controlled, but it is to be understood that any other fluid, whether a gas or liquid, may be used to test the permeability of textile packages in the present method of dyeing. Preferably, a stream of the testing medium is passed through a measuring orifice from a cham- 45 50 55

ber containing the medium at a predetermined constant pressure so that the fluid will be fed at a constant rate. The stream of fluid is then confined within the package so that it can escape 5 only through the porous core and the mass of material forming the package. The pressure will then accurately indicate a value of permeability of the package to the flow of the medium.

It has been found by experiment that the value 10 of permeability of a package by any particular testing medium, such as air, may be converted by constants to the permeability of the package by other fluids such as dyeing or other compounds or any fluid for treating textiles. It has further 15 been determined by experiment that the present method of testing packages accurately measures their relative permeability so that each package of a group having substantially the same permeability by test will pass the same amount of treating 20 fluid. For example, when a group of packages having substantially the same permeability as determined by test are subjected to a dye-liquor under pressure they will all take the same color shade, other variables being constant. 25 The present invention has for its particular object to attain a uniform permeability in all the packages within a permissible range to obtain a uniform treatment of all the packages in different batches. To this end the winding machine 30 spindles producing improperly wound packages as determined by the testing step are adjusted to correct the fault so that all the packages will have substantially the same permeability. Thus, only a few packages will fall outside of the permissible range of standard permeability when 35 tested and these packages are rewound. If a large number of packages are found to have a permeability greater or lesser than a predetermined standard when tested they may be grouped 40 together in separate batches. These batches may then be subjected to individual treatment under conditions proportional to their permeability as tested so that the same amount of fluid will pass through each package of the different groups to 45 uniformly treat all the packages.

The present drawings illustrate a preferred form of apparatus for testing the permeability of the individual textile packages. The apparatus includes a supporting bench or table 5 on 50 which a nozzle 6 is mounted for dispensing a stream of the testing fluid at a constant rate. The nozzle 6 is mounted in an aperture 7 in the table 5 and has a radial flange 8 which seats against the table top. The end of the nozzle 6 55 extending downwardly through the aperture 7 is formed as a threaded pipe-nipple 9 and a nut 10 screwed onto the nipple against a washer 11 abutting the bottom of the table secures the nozzle fixedly in place. The nozzle 6 has an axially-extending measuring orifice 12 through 60 which the testing fluid passes and a cylindrical extension 13 projecting upwardly from the flange 8 to form a closure plug for a purpose to be later described. The fluid, preferably air, is constantly supplied to the nozzle from a suitable source, not herein shown, through a conduit 14. Between the conduit 14 and nozzle 6 a needle-valve 15 and pressure-measuring chamber 16 are provided. The chamber 16 as herein illustrated is 65 constituted as a short pipe-nipple having one of its threaded ends connected to the nipple 9 on the nozzle 6 by a union 17. The needle-valve 15 has a suitable operating handle 18 and opposite 70 female pipe threads for connecting it to the pipe- 75

nipple forming the pressure chamber 16 and the conduit 14.

A pressure-indicating device is mounted in any convenient position as on the table 5 and preferably takes the form of a manometer tube 20 5 having a long arm 21 and short arm 22; but it is to be understood that other forms of pressure-indicating instruments may be substituted for that herein illustrated. The manometer tube 20 is mounted on an indicating board 23 which, in turn, is mounted on the table 5 by means of brackets 24. The board 23 is suitably marked with indicia to provide a scale 25 at its upper end while its lower end extends through an aperture 26 in the table 5 to position the scale to be readily observed by an operator. The manometer tube 20 is slidably supported on the board 23 by brackets 27 and 28 with its lower end resting on a vertically adjustable seat 29. The brackets 27 and 28 loosely embrace the manometer tube 20 so that it may be adjusted vertically by an adjusting screw 30 extending through a screw-threaded support 31 fixed to the board 23 and engaging the seat 29. In this manner the tube 20 may be adjusted on the board 23 so that the level of the fluid in the opposite arms 21 and 22 of the tube 20 may be brought into register at a point indicated on the scale at "L" when on pressure is applied.

The pressure in the chamber 16 is transmitted to the short arm 22 of the manometer tube 20 by 30 means of a flexible tube or conduit 36 having one end connected to a nipple 37 projecting laterally from the chamber 16 and its opposite end connected to the short arm 22 of the tube. As herein illustrated, the conduit 36 extends through 35 an aperture 38 in the table, but it will be understood that any other arrangement of the parts may be made whereby to transmit the pressure in the chamber 16 to the manometer tube 20. The needle-valve 15 is adjusted by means of the 40 handle 18 to permit a flow of the testing medium from the conduit 14 into the pressure chamber 16 at a constant rate. The medium will then flow from the pressure chamber 16 through the measuring orifice 12 of the nozzle 6 at a constant rate 45 to maintain a constant pressure in the chamber. The needle-valve 15 is set to maintain a normal level of the liquid in the long arm 21 of the manometer tube 20 in register with the "O" graduation on the scale 25 when the testing medium is 50 freely escaping through the nozzle 6.

The apparatus illustrated is particularly adapted for testing packages, such as indicated by the character P, wound on rigid, hollow, cylindrical cores C which are provided with a 55 series of rows of perforations for passing a treating fluid such as a dye-liquor during subsequent treatment. A package to be tested is mounted on the apparatus with its lower end abutting the upper face of the flange 8 surrounding the cylindrical plug 13 which is of such diameter as to provide a close fit with the interior of the core C. The plug 13 is of such length as to block the lowermost row of perforations in the core C and together with the seating of the core on the flange 60 8 seals the lower end of the package.

The opposite end of the rigid core C is sealed by a closure-plate 40 carrying a plug 41 for insertion into the interior of the core with a close fit in a manner similar to the plug 13. The closure-plate 40 and its depending plug 41 are adapted for movement toward and away from the end of the package and to this end are rigidly fixed to one end of an arm 42 by means of screws 43. The arm 42 is mounted on the upper end of a 70 75

reciprocable rod 44 by means of a hub 45 which is held against a shoulder 46 on the rod by a nut 47 screwed down on its threaded end. The rod 44 is supported in suitable bearings 48 and 49 carried by a bracket 50 which is fastened to the table 5 by means of bolts 51. The plate 40 and plug 41 are held from turning on the rod 44 by a key 52, see Fig. 2, and maintained in proper alignment with the nozzle 6 and plug 13 by a set-screw 53 extending through the bearing 48 and engaging a longitudinal slot 54 in the rod. The closure-plate 40 is normally held in spaced relation with respect to the end of the core C, as illustrated in Fig. 1, by a coil-spring 55 tensioned between an abutment 57 on the bracket 50 and a collar 58 fixed to the rod 44 by a set-screw 59. With the closure-plate 40 in its normal raised position packages of the textile material may be conveniently applied to the apparatus for a testing operation and thereafter removed therefrom.

The rod 44 extends through an aperture 64 in the table 5 and may be drawn downwardly against the action of the spring 55 to lower the closure-plate 40 into engagement with the open end of the core C by means of a foot-treadle 65 and connecting rod 66. The treadle 65 is of usual construction having one end pivoted as at 67 and a pedal 68 at its opposite end. The connecting rod 66 has bifurcated end members 69 and 70 screwed onto its threaded ends to provide for adjusting its length. The member 69 is pivotally connected to a tongue 71 at the lower end of the rod 44 by means of a clevis-pin 72 while the member 70 is similarly connected to the treadle 65 intermediate its ends by a clevis-pin 73. One form of the testing apparatus having now been described its mode of operation will next be explained.

The operator initially adjusts the apparatus for a testing operation by first moving the manometer tube 20 with respect to the scale-board 23 by means of the adjusting screw 30 until the level of the liquid in the two arms 21 and 22 registers with the normal level point indicated at "L" on the scale 25. The needle valve 15 is then opened by turning the handle 18 to permit the testing fluid to enter the chamber 16 and escape through the measuring orifice 12 in the nozzle 6. Due to the throttling effect of the measuring orifice 12 a pressure will be built up in the chamber 16 which is constant for a particular setting of the needle-valve 15. To provide a predetermined normal pressure in the chamber 16 the operator adjusts the needle-valve 15 until the liquid level in the long arm 21 of the manometer tube 20 registers with the graduation marked "O" on the scale 25. A package P is next mounted in position on the apparatus as shown in Fig. 1 with the lower end of its core C engaging the flange 8 and with the plug 13 extending into the lower end of the core.

The apparatus is then ready for a testing operation and the operator depresses the treadle 65 which acts through the connecting rod 66 and sliding rod 44 to lower the closure-plate 40 into sealing engagement with the upper end of the core C. The stream of testing fluid passing through the measuring orifice 12 is then confined within the core C and can only escape through the perforations therein and the interstices in the mass of yarn forming the package P. The position of the plugs 13 and 41 allows the escape of the testing fluid through that portion only of the package where the resistance to flow is uni-

form per unit of area. Due to the resistance of the package to the flow of the testing medium a pressure builds up in the package which causes an increase in the pressure in the measuring chamber 16 that is directly proportional thereto. Further, as the pressure necessary to force the testing fluid through the package is inversely proportional to the rate of flow of fluid through the package the degree of pressure in the chamber 16 is a measure of the permeability of the package. The pressure in the chamber 16 is transmitted through the conduit 36 to the short arm 22 of the manometer tube 20 and its degree is indicated on the scale 25 when it attains a constant value. After a particular package P has been tested the operator releases the treadle 65 and the spring 55 actuates the rod 44 to raise the closure-plate 40 to release the package. The package is then removed and another package applied and this package tested and the pressure observed in the same manner as above indicated.

The operator continues to test a plurality of packages and groups them in accordance with their degree of permeability as indicated by the pressure readings. It has been found that a certain tolerance in the permeability of the individual packages of a batch is permissible and that the permissible tolerance varies for different dye-liquors with which the packages are treated. Thus, those packages having substantially the same permeability within a predetermined range are grouped together for subsequent treatment. Those packages outside of the permissible range of permeability are either rewound or, when they occur in large numbers, are grouped together to form a separate batch or batches so that all the packages in an individual batch will pass the same amount of dye-liquor or other treating fluid and will be uniformly treated. Preferably the packages are dyed or otherwise treated in an apparatus for processing fibrous materials of the type illustrated and described in United States Patent Application of Royal Little et al. Serial No. 56,338 filed December 27, 1935, Patent Number 2,125,937, dated August 9, 1938. For example, a batch of packages having substantially the same permeability within permissible limits are mounted on hollow perforated holders in tandem and the loaded holders supported in a kier, either on a portable carrier or otherwise, with one of their ends in communication with a chamber for supplying a dye or other treating liquor under pressure. The dye or other treating liquor is then forced radially through the perforated holders and packages mounted thereon for a predetermined period of time. Due to the fact that the packages all have the same permeability the same quantity of the treating liquor will pass through each of the packages. It has been found in actual practice that when so treated all the packages will be uniformly treated and when dyed will take the same color shade. Groups of packages having a greater or lesser permeability may be treated in the same way, but with the conditions of treatment such as the pressure and/or the period of treatment increased or decreased in proportion to the permeability of the batch so that the same predetermined quantity of the liquor will pass through each package of this group as passes through the packages of normal permeability. Thus all the packages of different batches will be uniformly treated.

From the foregoing description of the invention it will be observed that a novel method of

dyeing or similarly treating textile materials has been provided including the step of accurately measuring the relative permeability of each package of the material to the flow of a fluid 5 as indicated by the pressure necessary to force a testing fluid through the package at a constant rate. It will also be observed that by testing the relative permeability of a plurality of packages a subsequent uniform treatment may be given to 10 all the packages in dyeing, bleaching, mordanting, or other treating processes. It will further be observed that the present invention provides for testing the packages with great facility by a series of simple operations that may be performed by an unskilled person with unerring 15 accuracy.

Various modifications may be made in the herein described method and in the form of the apparatus illustrated without departing from the 20 spirit or scope of the invention. Therefore, without limiting ourselves to the exact embodiments described and illustrated, we claim:

1. The method of uniformly treating a plurality of hollow packages of textile material with 25 a dye-liquor which comprises passing a confined stream of testing fluid through each package, measuring the pressure of said testing fluid caused by the resistance of the package to the flow thereof, grouping those packages having 30 substantially the same permeability as measured by the pressure of said testing fluid, and passing a dye-liquor through the selected group of pack-

ages under pressure to cause the material of all the packages to be uniformly treated.

2. The method of uniformly treating a plurality of hollow packages of textile material with a dye-liquor which comprises passing a confined stream of testing fluid through each package, measuring the pressure of said testing fluid caused by the resistance of the package to the flow thereof, grouping those packages having substantially the same permeability as measured 1 by the pressure of said testing fluid, and treating the several groups of packages having different permeability by separately passing a dye-liquor through the packages of the different groups under such conditions of pressure of the dye- 1 liquor, duration of treatment, or strength of the dye-liquor as will uniformly treat the material in all the packages.

3. The method of dyeing hollow packages of textile material which comprises testing the packages for permeability by passing a confined stream of air through each package and measuring the pressure of said air-stream caused by the resistance of the package to the flow thereof, grouping those packages having substantially 2 the same permeability as measured by the pressure of said air stream, and passing a dye-liquor under pressure through the selected group of packages to cause the material in all the packages to be dyed to a uniform shade. 3
